UNITED STATES PATENT OFFICE.

HIRAM B. CANNON, OF METUCHEN, NEW JERSEY, ASSIGNOR TO THE CARBORUNDUM COMPANY, OF NIAGARA FALLS, NEW YORK, A CORPORATION OF PENNSYLVANIA.

FLUID HEATING FURNACE.

Application filed May 14, 1924. Serial No. 713,187.

This invention relates to apparatus or furnaces for burning pulverized fuel and, in the embodiment shown herein the apparatus is designed with special reference to the heating fluids contained in and circulating through tubes arranged in operative relation to a heat-radiating combustion chamber. It is the general purpose and object of the invention to provide a furnace or apparatus which will be capable of operating with pulverized fuel and which apparatus will be so constructed and arranged as to utilize a high percentage of the heat resulting from the combustion of the fuel; which will enable the heating to be accomplished with such fuel and with a considerable reduction of furnace-volume or space over that usually required for equivalent heat capacity; also to provide an apparatus which will enable fluids contained in and circulating through tubes to be heated efficiently by radiant heat as well as by such heat in conjunction with the exhaust gases.

In the drawings, Fig. 1 represents a vertical sectional view through a fluid heating apparatus embodying the invention; Fig. 2 a transverse sectional view corresponding to the line 2—2 of Fig. 1; Fig. 3 a plan view, with parts broken away, of the combustion chamber shown in the preceding views; and Fig. 4 an enlarged transverse sectional view through the said combustion chamber.

The invention shown herein is embodied in a fluid heating furnace or apparatus of the type shown in co-pending application No. 713,186 filed May 14, 1924, which shows a furnace or apparatus of the same character as the one shown herein except that it is adapted for the burning of liquid fuel, such as oil. The invention as embodied herein is especially and primarily designed for the efficient burning of pulverized fuel, although certain features of construction (and particularly of the combustion chamber) are applicable to and useful in connection with the combustion of other fuels.

Describing the various parts by reference characters, 1 denotes the shell or envelope of a furnace, the said shell being formed of heat-resistant material having low heat conductivity, enabling it to reflect heat without undue absorption thereof. Material suitable for such shell is siloel mortar, magnesia covering, and similar material. The shell is closed at its front end by a head 2 having an opening 3 for the reception of a wind box 4,

which fits within the said opening and is provided at its rear end with a neck 5. At its rear end, the shell 1 is provided with a stack 6, for exhaust gases.

The shell 1 is shown as rectangular in cross section and is provided near the front and rear ends and near the middle thereof with inwardly-extending supporting and stabilizing frames or piers 7, the said frames or piers being seated within grooves 7^a formed in the top, bottom, and sides of the shell. Between the bottom of each frame or pier and the bottom of the groove provided therefor there extends a supporting metal strap 8, the said strap extending upwardly in and through the side walls of the shell 1.

Projecting through the front of the wind box 4 is a burner nozzle 9, the said nozzle communicating with a T coupling 10 to which are connected a supply 11, for pulverized fuel, and a pipe 12 supplying air under pressure for forming a primary mixture of air and fuel. Communicating with the bottom of the wind box is a pipe 13 for supplying additional or "secondary" air to the wind box.

The nozzle 9 is arranged axially with respect to the neck 5 and preferably extends to approximately the rear of such neck. This neck in turn fits within a sleeve 14 formed with and projecting from the front of the combustion chamber. This combustion chamber is generally of the type shown in the patent to Hiram B. Cannon No. 1,371,774 issued March 15, 1921, and comprises a front wall 15 beyond which the sleeve 14 extends; a rear wall 16, a bottom wall 17, a top wall 18, side wall 19, and a wall 20 intermediate between the side walls and extending rearwardly from one side of the sleeve 14 to a point adjacent to but spaced from the rear wall 16 and forming a lateral mixing and combustion passage A and a lateral mixing and combustion passage B, with a connecting passage C around the rear end of the partition wall. These passages constitute a combustion space into the receiving end of which the mixture of pulverized fuel and air is introduced, and the delivery end of which is provided with an outlet D through which the products of combustion are discharged. The top, bottom and side walls are formed of separate slabs, the side wall slabs being seated in grooves 17^a and 18^a formed in the top and bottom wall slabs respectively. The top and bottom wall slabs are provided with seats 19^a for

describing the various parts by reference characters, 1 denotes the shell or envelope of a furnace, the said shell being formed of heat-resistant material having low heat conductivity, enabling it to reflect heat without undue absorption thereof. Material suitable for such shell is siloel mortar, magnesia covering, and similar material. The shell is closed at its front end by a head 2 having an opening 3 for the reception of a wind box 4,

the partition-wall slabs 20. The various parts of which the combustion chamber 1 is composed are made of material having great heat-absorbing and radiating qualities. The material which is preferred for use for this purpose is silicon carbide or carborundum. If desired, cement of like material as the slabs may be employed at the joints therebetween.

The combustion chamber extends from a point closely adjacent to the front wall 2 of the casing to a point adjacent to the rear wall 2^a thereof, being supported upon the bottom portions of the frames or piers 6 and having its side walls closely adjacent to the side portions of said frames.

By the construction thus far shown and described, it will be apparent that the combustion chamber is supported above the bottom of the shell 1 and that it is spaced from the sides of such shell, a considerable space being left between the top of the chamber and the upper portions of the frames or piers 6. The space within the shell 1 and surrounding the combustion chamber is utilized in a very efficient manner for the purpose of heating fluid. The fluid to be heated is conducted through coils of pipe surrounding the combustion chamber and forming an absorbent screen. 21 denotes a supply pipe leading to the coil, the coil comprising lengths 22 of tubing extending longitudinally of the shell and connected at their ends by bends 23, as is ordinary in heating apparatus. The tubes 22 are so arranged as to provide an outer series of such tubes surrounding the combustion chamber and jointly supported by the frames or piers 7 and by the inner wall of the shell 1, with an inner series of such pipes also surrounding the combustion chamber and mounted within the frames or piers 7, which frames or piers are also preferably of silicon carbide or carborundum. It will be noted further that the tubes in the inner series are staggered with respect to those in the outer series, this arrangement permitting of a maximum absorption of radiant and reflected heat by the tubes. The fluid heated within the coil is delivered to an outlet pipe 24 leading to a suitable point of use.

It will be noted that the outlet D is located closely adjacent to the front wall 15, whereby the products of combustion may pass upwardly and rearwardly in operative relation to the tubes 22 and be delivered to the stack 6.

The apparatus thus far disclosed may be suspended by the straps 8 from longitudinal I-beams 25 which are supported on the upper transverse members 26^a of supporting frames, the vertical members of which are indicated at 26. The upper ends of the metal straps will be looped about the members 25, as indicated at 8^a.

In order to accommodate the furnace or apparatus for the use of pulverized fuel, the combustion chamber should incline down-

wardly from front to rear, in order to prevent an undesirable accumulation of slag therewithin, the chamber being provided with an outlet E formed at the lower end of the bottom wall 17. Extending downwardly from and surrounding this outlet is a neck F which communicates with an ash pit G normally sealed by a door G', the said pit being shown as formed within a large pier H upon which the rear end of the furnace shell is supported. The entire furnace, with the combustion chamber and the fluid heating tubes, is supported in the downwardly inclined position referred to hereinbefore, the rear and lower end of the furnace assembly being supported by the pier H.

In the operation of the apparatus thus far described, pulverized fuel will be delivered through the nozzle 9, neck 5, and sleeve 14, into the combustion passage A, and will burn therein and in the passages C and B. For best results, the pulverized fuel and air will be so controlled that the flame will travel the full length of the combustion passages, with the tip of the flame at the outlet D. This insures combustion throughout the entire effective length of the combustion chamber, including the three passages thereof. As a result, the chamber will be uniformly heated throughout its extent, enabling it to operate at maximum efficiency. The adjustment of the air and fuel to secure this result will be facilitated by providing the front wall 2 with a mica-covered peep hole located above the outlet D. The combustible mixture within and throughout the length of the passage B will be heated by the passage A and the partition 20, facilitating the quick and complete combustion of the mixture in the passage B.

The tubes 22 will be heated by the radiant heat of the combustion chamber as well as by the products of combustion delivered through the outlet D; but the length of the combustion chamber and the heat radiating qualities of the same are such that, by the time the flame has reached the outlet D, complete combustion of the mixture will have been obtained and the temperature of the products delivered through the outlet D will have been so reduced that they may be discharged directly against the heat absorbing tubes without injury thereto. By employing material of high-heat-absorbing and radiating qualities for the frames or piers 6 the

said frame or piers will be quickly heated and will transfer such heat to the tubes and to the fluid therewithin. Furthermore, the employment of a heat-resistant shell or envelope 1 of low heat conductivity enables the said shell or envelope to reflect, without great absorption, heat radiated thereto by the combustion chamber. The rays of heat directed against this envelope or casing will be reflected thereby to the tubes and absorbed by the latter.

Owing to the fact that the combustion chamber is made of slabs of silicon carbide, it will be advisable, if not necessary, to provide stabilizing members 28 beneath the joints between adjacent slabs, in addition to the frames or piers 6. These members may, and preferably will, be made of silicon carbide.

The particular structure shown herein will 10 produce a fluid-heater of great efficiency. Where air, for instance, is heated, calorized tubes will preferably be used for the coil. Furthermore, by substituting headers for the bends 23 and by connecting the tubes 22 to 15 such headers, the structure will produce a water tube boiler having great efficiency.

When operating at a high rate of combustion, a portion of the ash resulting from the combustion of the pulverized fuel is slagged 20 and, because of the great heat radiation of the combustion chamber and heat absorption by the fluid tubes and envelope surrounding such chamber, this slag is cooled and deposited upon the inner walls and partition of 25 the combustion chamber to a depth of approximately five-sixteenths inch. This slag coating is shown at 27 in Fig. 4. This coating or deposit does not build up any deeper or thicker because its presence tends to restrict 30 the flow of heat to the furnace walls and, by so doing, a temperature is automatically built up which keeps the slagged ash molten beyond the depth mentioned.

Due to the inclination of the furnace and 35 combustion chamber, this molten ash or slag flows to the rear of the combustion chamber, where it drops into the ash pit G, whence it is drawn off periodically.

The use of silicon carbide for the combustion chamber prevents the latter from storing 40 up heat to an extent which will bring its temperature as high as the fusing point of the ash in the pulverized fuel; so that, while the interior of the combustion chamber will be 45 entirely covered with a protective ash glaze, the temperature of the walls of the combustion chamber will never be as high as the fusing point of the ash in the pulverized fuel, and hence there will be no reaction between 50 the ash and the furnace walls, to cause injury to or destruction of the latter. On the contrary, these walls will be covered with a protective coating of ash glaze or slag which 55 protects the walls from a wearing and abrasive action of the ash thereagainst.

Should this protective coating crack, when 60 the combustion chamber cools off after use, at the joints between the slabs of which the said chamber is composed, at the next operation 65 of the chamber, this coating will become molten to a sufficient extent to cause it to re-unite and close the cracks or joints thus formed because of the cooling operation.

Notwithstanding the fact that the production 70 of ash is a necessary incident to the use

of pulverized fuel when the combustion chamber disclosed herein is operating under the most efficient conditions, there will be no deposit of molten ash upon the tubes surrounding the said chamber. Such ash as may be 75 discharged with the products of combustion through the outlet D, will be fine ash and will be discharged at a temperature insufficient to melt or fuse the same.

The construction disclosed herein realizes 75 the general advantages of securing complete combustion of the fuel at very high combustion capacity; transmitting nearly 60 per cent, by radiation, of the total heat resulting from the combustion in the fuel to the tubes or other absorbing media; heating the combustion chamber uniformly throughout its length with the elimination of localized heating; reducing the sensible heat of the exhaust gases to an extent to enable them to heat each 80 addition to the combustion chamber without injury; reducing the dimensions of the boiler or other apparatus as compared with other apparatus or installations for like purposes; protecting the surrounding tubes or other 85 media from the oxidizing action of flames impinging thereagainst. In addition, I accomplish these objects and realize these advantages in connection with the combustion of pulverized fuel and without injury to the 90 combustion chamber or to the surrounding heat-absorbing media.

In order to radiate heat efficiently to the tubes or absorbent screen and to the interior of the casing 1, the refractory material of 100 which the combustion chamber is composed should have a thermal conductivity in excess of $0.006 \text{ cal/cm}^3/\text{sec}^{\circ}\text{C}$; and, as is well known, the thermal conductivity of silicon carbide is in excess of that expressed by this 105 formula. Other refractories having a thermal conductivity in excess of that specified are fused aluminum oxide (Al_2O_3) and fused magnesium oxide (MgO).

Having thus described my invention, what 110 I claim is:

1. A fluid-heating apparatus comprising a combustion chamber composed principally of refractory material having a thermal conductivity in excess of $0.006 \text{ cal/cm}^3/\text{sec}^{\circ}\text{C}$, 115 a plurality of tubes substantially surrounding the said combustion chamber and arranged in close proximity thereto and providing an absorbent screen for the radiant heat therefrom, the said combustion chamber and the said screen being inclined downwardly from the front to the rear thereof and the said combustion chamber being provided at the bottom of the rear portion thereof with an outlet for molten ash or slag, means for sealing said outlet, and means for supplying a mixture of pulverized fuel and air to the front of said combustion chamber, the said combustion chamber having a combustion space therein receiving at one end the mixture 120 125 130

of pulverized fuel and air, and provided at its opposite end with outlet means through which all of the products of combustion are discharged.

5. 2. A fluid-heating apparatus comprising an elongated combustion chamber composed principally of refractory material having a thermal conductivity in excess of 0.006 cal/cm³/sec/°C., a plurality of tubes extending longitudinally of and substantially parallel with the said combustion chamber and substantially surrounding the said chamber in close proximity thereto and forming an absorbent screen for the radiant heat therefrom, the said combustion chamber and the said tubes being inclined downwardly from the front to the rear thereof and the said combustion chamber being provided at the bottom of the rear portion thereof with an outlet for molten ash or slag, and means for supplying a mixture of pulverized fuel and air to the front of said combustion chamber, the said combustion chamber having a combustion space therein receiving at one end the mixture of pulverized fuel and air, and provided at its opposite end with outlet means through which all of the products of combustion are discharged.

3. A fluid-heating apparatus comprising an elongated combustion chamber composed principally of refractory material having a thermal conductivity in excess of 0.006 cal/cm³/sec/°C., and a plurality of tubes extending longitudinally of and substantially parallel with the top and sides of said combustion chamber in close proximity thereto and forming an absorbent screen for the radiant heat therefrom, the said combustion chamber and the said tubes being inclined downwardly from the front to the rear thereof and the said combustion chamber being provided at the bottom of the rear portion thereof with an outlet for molten ash or slag, and means for supplying a mixture of pulverized fuel and air to the front of said combustion chamber, the said combustion chamber having a combustion space therein receiving at one end the mixture of pulverized fuel and air, and provided at its opposite end with outlet means through which all of the products of combustion are discharged.

4. A fluid-heating apparatus comprising an outer casing of heat-resistant and heat-reflecting material, a combustion chamber composed principally of a refractory material having a thermal conductivity in excess of 0.006 cal/cm³/sec/°C. mounted within the said casing, fluid-containing tubes arranged between the said chamber and the said casing and substantially surrounding the former, the said combustion chamber being downwardly inclined from the front to the rear thereof and provided at the bottom of the rear portion thereof with an outlet for molten ash or slag leading to the atmosphere and

means for sealing the same, and means for supplying a mixture of pulverized fuel and air to the front of said combustion chamber, the combustion chamber, the tubes and the said casing being so arranged that the tubes will be heated efficiently by radiation from the combustion chamber and by radiant heat received by the interior of said casing and reflected thereby to said tubes.

5. A fluid-heating apparatus comprising an outer casing of heat-resistant and heat-reflecting material, a combustion chamber composed principally of refractory material having a thermal conductivity in excess of 0.006 cal/cm³/sec/°C. and mounted within the said casing, fluid-containing tubes arranged between the said chamber and the said casing, the said combustion chamber being downwardly inclined from the front to the rear thereof and provided at the bottom of the rear portion thereof with an outlet for molten ash or slag leading to the atmosphere and means for sealing the same, and means for supplying a mixture of pulverized fuel and air to the front of said combustion chamber, the combustion chamber, the tubes and the said casing being so arranged that the tubes will be heated efficiently by radiation from the combustion chamber and by radiant heat received by the interior of said casing and reflected thereby to said tubes.

6. In a fluid-heating apparatus, the combination of an outer casing of heat-resistant and heat-reflecting material, a combustion chamber of refractory material having a thermal conductivity in excess of 0.006 cal/cm³/sec/°C. within said casing, fluid-containing tubes arranged between the said chamber and the said casing, the said tubes being staggered, thereby to produce an absorbent screen, the said combustion chamber being downwardly inclined from the front to the rear thereof and provided at the bottom of the rear portion thereof with an outlet for molten ash or slag leading to the atmosphere and means for sealing the same, and means for supplying a mixture of pulverized fuel and air to the front of said combustion chamber, the combustion chamber, the tubes and the said casing being so arranged that the tubes will be heated efficiently by radiation from the combustion chamber and by radiant heat received by the interior of said casing and reflected thereby to said tubes.

7. A fluid-heating apparatus comprising an outer casing of heat-resistant and heat-reflecting material, piers mounted within said casing and projecting inwardly from the inner wall thereof, a combustion chamber composed principally of refractory material having a thermal conductivity in excess of 0.006 cal/cm³/sec/°C. and extending longitudinally of said casing through and mounted upon said piers, fluid-containing tubes interposed

between the said chamber and the said casing and mounted in the said piers, the said tubes being arranged in inner and outer series, the tubes in one series being staggered with respect to those in another series, the casing, tubes and combustion chamber being downwardly inclined from the front to the rear thereof and the chamber being provided at the bottom of the rear portion thereof with an outlet for molten ash or slag leading to the atmosphere and means for sealing the same, and means for supplying a mixture of pulverized fuel and air to the front of said combustion chamber, the combustion chamber, the tubes and the said casing being so arranged that the tubes will be heated efficiently by radiation from the combustion chamber and by radiant heat received by the interior of said casing and reflected thereby to said tubes.

8. A combustion chamber having front, back, top, bottom and side walls, with a vertical partition extending between the top and bottom walls and interposed between the side walls and extending from the front wall toward but spaced from the rear wall to provide a passageway therearound, the said combustion chamber being provided with an inlet for a combustible mixture in the front wall at one side of said partition and being provided with an outlet adjacent only the said front wall at the opposite side of said partition, the said combustion chamber being composed principally of refractory material having a thermal conductivity in excess of 0.006 cal/cm²/sec/°C., and means for supplying such combustible mixture through the first mentioned opening.

9. A combustion chamber having front, back, top, bottom and side walls, with a ver-

tical partition extending between the top and bottom walls and interposed between the side walls and extending from the front wall toward but spaced from the rear wall to provide a passageway therearound, the said combustion chamber being provided with an inlet for a combustible mixture in the front wall at one side of said partition and being provided with an outlet in the top thereof adjacent to the front wall only and on the opposite side of the partition, the said combustion chamber being composed principally of refractory material having a thermal conductivity in excess of 0.006 cal/cm²/sec/°C., and means for supplying such combustible mixture through the first mentioned opening.

10. A fluid-heating apparatus comprising an outer casing of heat-resistant and heat-reflecting material, a combustion chamber composed principally of silicon carbide mounted within the said casing, fluid-containing tubes arranged between the said chamber and the said casing, the said combustion chamber being downwardly inclined from the front to the rear thereof and provided at the bottom of the rear portion thereof with an outlet for molten ash or slag leading to the atmosphere and means for sealing the same, and means for supplying a mixture of pulverized fuel and air to the front of said combustion chamber, the combustion chamber, the tubes and the said casing being so arranged that the tubes will be heated efficiently by radiation from the combustion chamber and by radiant heat received by the interior of said casing and reflected thereby to said tubes.

In testimony whereof, I hereunto affix my signature.

HIRAM B. CANNON.
